UNITED STATES PATENT OFFICE.

WALTER E. WRIGHT, OF CLEVELAND, OHIO.

BRUSH-HOLDER.

1,204,531.

Specification of Letters Patent. Patented Nov. 14, 1916.

Application filed December 30, 1915. Serial No. 69,322.

To all whom it may concern:

Be it known that I, WALTER E. WRIGHT, a citizen of the United States of America, residing at Cleveland, in the county of 5 Cuyahoga and State of Ohio, have invented certain new and useful Improvements in Brush-Holders; and I hereby declare the following to be a full, clear, and exact description of the invention, such as will enable others skilled in the art to which it pertains to make and use the same.

This invention relates to improvements in brush-holders, and pertains more especially to a brush-holder comprising an externally 15 tapering head adapted to fit internally of the upper end of an upwardly flaring cup containing turpentine or other liquid for protecting the bristles of the brush which is to be supported from said holder.

20 One object of this invention is to have said head comprise two separable sections adapted to embrace the stock of the brush and facilitate the application of a brush to and its removal from the brush-holder.

25 Another object is to provide said head with suitable packing and thereby prevent evaporation of the liquid in the cup adapted to receive the brush to be supported from said head.

30 Another object is to render a brush supported from said head only removable from the head upon the separation of the aforesaid sections of the head.

With these objects in view, and to the end 35 of attaining any other advantage herein-after appearing, this invention consists in certain features of construction, and combinations and arrangement of parts, herein-after described in this specification, pointed 40 out in the claims, and illustrated in the accompanying drawings.

In said drawings, Figure 1 is a side view of a brush-holder embodying my invention, and shows a brush supported from said 45 holder and shows the brush-holder within the upper end-portion of and removably supported from a cup containing turpentine or liquid for preserving the bristles of the brush. In this figure the cup is shown in 50 section and portions of the brush-holder are broken away and in section to more clearly show the construction. Fig. 2 is a top plan relative to Fig. 1, and portions are broken away and in section in Fig. 2 to more clearly 55 show the construction. Fig. 3 is a central

vertical section taken through the cup and through the brush-holder along the line 3—3, Fig. 1, and shows the brush in elevation. Fig. 4 is a transverse section on line 4—4, Fig. 3. Fig. 5 is a view in perspective 60 of one of the sections of the brush-holder. Fig. 6 is a vertical section on either line 6—6, Fig. 1.

Referring to said drawings, A (see Figs. 1 and 3) indicates an upwardly flaring cup 65 containing turpentine or other liquid, and a indicates the level of said liquid.

My improved brush-holder comprises a head composed of sections B and shown in Figs. 1, 2, 3, 4 and 6 as fitting internally of 70 the upper end-portion of the cup A and tapering externally toward its inner end. Said head is provided centrally with an aperture b which extends from the outer end to the inner end of the head. Preferably 75 said head is divided centrally of said aperture, as at 8, (see Figs. 2, 3, 4, and 6) into two separable sections B which are shown embracing opposite portions respectively of the stock C of a brush which is shown supported from said head and has its bristles 10 depending into the liquid a in the cup A. The handle 12 of the brush is arranged externally of the cup.

The head-sections B are shown provided 85 at the upper or outer end of the head with shoulders 13 facing in the direction of the inner end of the head and overlapping the top of the stock C of the brush, as shown in Fig. 6. One of the head-sections B is shown 90 detached in Fig. 5. It will be observed (see Figs. 1 and 5) that each head-section B is provided with sloping internal surfaces 14 arranged between the inner end of the head and the shoulders 13 of said head-section and 95 facing in the direction of the outer end of the head, and said surfaces are shown overlapped in Fig. 1 by the stock C of the brush. It will be observed therefore that a separation of the head-sections B is required to 100 interpose the stock of the brush between them, and obviously by the construction hereinbefore described a brush can not be removed from the brush-holder without first separating said head-sections.

To prevent evaporation of the liquid contained in the cup A the brush-holder is provided with suitable packing. Preferably the brush-holding head is provided externally with a layer 15 of packing,—such, for in- 110

stance, as a strip of leather,—which extends around the head. Said head is shown provided internally between the inner end of the head and the shoulders 13 with a layer 5 16 of packing,—such, for instance, as a strip of leather,—extending around the aperture *b* in the head. Preferably each head-section B is provided at its inner face with an intermediate layer 17 of packing,—such, for 10 instance, as a strip of leather,—extending between and connecting with the aforesaid internal and external packing-layers 15 and 16. The packing 17 of one of the head-sections B is shown arranged at one side 15 of the aperture *b*, and the packing 17 of the other of said sections is arranged at the opposite side of said aperture.

Preferably each head-section B is provided with a dowel-pin 18 projecting into a 20 cavity 20 in the other head-section, and the pin 18 and the cavity 20 of each head-section are arranged at opposite sides respectively of the aperture *b*.

It will be observed that the dowel-pins 25 18 constitute means for preventing displacement of the head-sections independently of each other.

What I claim is:—

1. In a brush-holder for a cup, a head 30 adapted to enter the upper end-portion of and be removably supported from the cup and provided with an aperture which extends from the outer end to the inner end of the head and divided at said aperture 35 into two separable sections adapted to embrace the stock of a brush, said sections being provided at the outer end of the head with shoulders facing in the direction of the inner end of the head.
- 40 2. In a brush-holder for a cup, a head adapted to enter the upper end-portion of and be removably supported from the cup and provided with an aperture which extends from the outer end to the inner end 45 of the head and divided at said aperture into two separable sections adapted to embrace the stock of a brush, said head being provided at its outer end with shoulders which face in the direction of the inner end 50 of the head and having internal sloping

surfaces which face in the direction of the outer end of the head.

3. In a brush-holder for a cup, a head adapted to be removably inserted into the upper end-portion of the cup and having 55 an aperture which extends endwise of and through the head, said head being divided at said aperture and from end to end of the head into two laterally separable sections and provided at its outer end with a shoulder which faces in the direction of the inner end of the head.

4. In a brush-holder for a cup, a head adapted to be removably inserted into the upper end-portion of the cup and having 65 an aperture which extends from the outer end to the inner end of the head, said head being divided at said aperture into two separable sections and provided at its outer end with a shoulder which faces in the direction of the inner end of the head and having means for preventing endwise displacement of the head-sections independently of each other.

5. In a brush-holder for a cup, a head 75 adapted to fit internally of the upper end-portion of the cup and having an aperture extending from the outer end to the inner end of the head, which head has an external layer of packing extending around the head 80 and an internal layer of packing extending around the aforesaid aperture, said head being divided at said aperture into two separable sections adapted to embrace the stock 85 of a brush, one of said sections being provided at its inner face at one side of said aperture with a layer of packing connecting the aforesaid internal and external layers of packing together, and the other of said sections being provided at its inner 90 face at the opposite side of said aperture with a layer of packing connecting said external and internal layers together.

In testimony whereof, I sign the foregoing specification, in the presence of two witnesses.

WALTER E. WRIGHT.
